UNITED STATES PATENT OFFICE

AUGUST KRASTIN, OF CLEVELAND, OHIO, ASSIGNOR TO WALTER E. MILESTONE, OF CLEVELAND, OHIO

HELICOPTER TOY DEVICE

Application filed September 26, 1931. Serial No. 565,319.

The primary object of this invention is to provide an improved launching device for an aerial toy. A specific object is to provide an improved device of this character, particularly an improvement in serviceability and economy of manufacture. For convenience, the present embodiment of the invention will be referred to as a pistol, which it resembles.

10 Other objects and features of the invention will become apparent from the following description relating to the accompanying drawing, wherein I have shown my preferred form. The essential characteristics 15 are summarized in the claims.

Referring to the drawing, Fig. 1 is a side elevation of the pistol; Fig. 2 is a central longitudinal sectional view thereof; Fig. 3 is a sectional view through a ratchet mechanism, as indicated by the line 3-3 on Fig. 1; Fig. 4 is a transverse sectional view of the handle, and Fig. 5 is a cross sectional view showing a modified means of mounting one of the parts in a general casing.

25 Referring again to the drawing, 1 is a main casing, substantially cylindrical, as shown, and in which, extending therethrough, is a fixed spindle 2, the spindle having a suitable rigid mounting at 3 in one end 30 of the casing. The novel construction of the casing and spindle mounting will be herein-after described. The casing 1 rotatably supports a revolving barrel 4 surrounding the fixed spindle 2 and which contains a pro-

35 pelling spring 5 which is wound up on the spindle by manually rotating the barrel. The spring is then locked in wound-up position by suitable detent mechanism within the casing 1. The projectile, as shown, com-

40 prises a helicopter device H provided with a suitable number of blades, the central portion having openings, one for receiving one end of the spindle 2 which projects beyond the barrel 4 and the other for receiving a 45 driving projection 6 mounted in a closure member 7 rigidly secured in the outer end of the barrel. The action of the pistol, when the spring is released, is to rapidly turn the projectile, thus forcing it off the barrel 4 by 50 air pressure on the blades.

The detent mechanism above mentioned comprises a ratchet wheel 10 fixed to the barrel 4. The barrel 4 preferably comprises a single strip of sheet metal formed into generally cylindrical form, one end of the barrel so formed being secured to the ratchet wheel 10. The other end of the barrel is suitably fastened as by solder to a reduced portion 7' on the closure member 7, which reduced portion forms a shoulder as clearly shown in Fig. 2, definitely locating the closure member. Any suitable means may be employed to secure the end of the spring opposite the ratchet wheel to the spindle 2, as at 11.

A feature of the invention is the manner in which the barrel 4 is secured to the ratchet wheel 10. The inner end of the barrel has an outwardly extending flange 4' which is embraced and secured between the wheel 10 and an annular disc 12; there being a suitable number of rivets 13 provided to hold the wheel 10 and disc 12 together—see Figs. 2 and 3. The inner end of the spring is secured to one of the rivets as at 13'—Fig. 3. This arrangement obviates the necessity for soldering as heretofore done, both to secure the barrel and ratchet wheel and to attach the end of the spring 5. The present arrangement thereby permits the use of oil tempered spring stock—which does not solder well—but is much less expensive than piano wire spring stock, and further, the matter of assembly is greatly facilitated.

55 The barrel 4 is prevented from being removed from the casing 1 by reason of the disc 12 and is also secured against endwise movement inwardly of the casing by a suitable shoulder at 2' on the spindle, the wheel being perforated to turn easily on the spindle 2 adjacent the shoulder, as shown.

60 The spindle pivotally supports a trigger 14 on a suitably flattened portion of the spindle, there being a suitable pivot pin through this flattened portion at 15, and the trigger has a lateral extension at 16 forming a pawl for engaging the teeth of the ratchet wheel to thereby maintain the spring in tension when wound up. A suitable spring 17 is interposed between the trigger and spindle to 65

maintain the pawl portion of the trigger in engagement with the ratchet teeth.

The casing 1 comprises a single strip of sheet metal 20 suitably formed substantially cylindrically, the ends of the strip being separated from each other a sufficient distance to form a free guide for the trigger as at 21. According to previous practice, the guide for the trigger was subject to being collapsed on the trigger due to springing of the material comprising the side walls of the cylinders. I overcome this difficulty by providing the end disc members 25 and 26 of the cylinder with channels which embrace the end edges of the strip 20 both inwardly and outwardly, thus solidly holding the strip in its cylindrical form. I accomplish this simply by continuously flanging the outer edges of the discs 25 and 26, forming shoulders at 23 inwardly of the strip 20, and at 24 outwardly of the strip. The strip 20 and end discs may be secured in the assembled relationship shown by means of solder.

The spindle 2 has a reduced end at 27 threaded to receive suitable nuts 3, previously referred to, one being a lock nut, by which means the spindle is held in fixed relationship to the casing and very rigidly. It is a new thought in this construction to support the spindle entirely by the casing.

As an alternative construction of the spindle mounting,—see Fig. 5—this comprises a threaded boss formed in the end disc 25 at 25', the threaded end of the spindle engaging the threads in the boss. In adopting this form, the manner of assembly of the pistol is somewhat different, it being necessary to first thread the spindle into the end disc 25, together with its associated ratchet parts, including the barrel 4. Afterward the formed cylinder member 20 and the end disc 26 are secured in place as above described.

As shown in Fig. 4, the handle preferably comprises two substantially complementary shells of sheet metal 30 which fit into each other at their marginal edges in telescoping relationship; see overlapping portions of both shells at 30'. The shells may be blanked out on identical dies and one is simply formed slightly larger than the other at its edge so as to receive the smaller dimensions of the other shell. Each shell has an ear 31, the two ears lying in a common plane and provided with suitable means, such as an opening at 32 for receiving attaching screws or rivets, screws being shown at 28 adapted to pass through the end disc 25 and to be secured thereto by threads formed in the disc, or by separate nuts, if desired.

60 I claim:—

1. A propelling device for a spinning projectile, comprising a fixed member and a rotatable member, one member surrounding the other, a torsion spring interposed between and operatively connected to said mem-

bers, detent mechanism including a toothed wheel on the rotatable member to hold the spring in tension under the control of the user, said rotatable member being adapted to engage the projectile to spin it, a substantially cylindrical casing containing said detent mechanism and comprising a single piece sheet metal strip, and end discs supporting the strip, the said rotatable member being guided for rotation in one of said end discs 75 and there being means securing the fixed member in rigid relationship to the other disc, each of said end discs being recessed near its periphery to closely embrace respective marginal edges of said strip and rigidly hold the strip interiorly and exteriorly in position about the detent mechanism, the extremities of the strip being held in spaced relationship by said discs, said detent mechanism including a trigger adapted to engage 85 the toothed wheel and being mounted within said casing and projecting between said ends of the strip.

2. In a propelling device for a spinning projectile, two concentric relatively rotatable members, one being fixed, a torsion spring interposed between and operatively connected to said members, the rotatable member having means to engage such projectile for spinning the same when the spring is released, a 90 casing in which said relatively rotatable members are mounted, detent mechanism within the casing and having a releasing trigger extending outwardly therefrom, said casing comprising a single strip of sheet metal 100 forming the side wall for the casing and with its ends separated to embrace and guide the trigger, end members in which the first mentioned members are respectively mounted, said end members having oppositely facing grooves receiving respective marginal edges of said strip and embracing the same interiorly and exteriorly thereof, and means for holding said end members in rigid relationship to said strip.

3. In a propelling device for a spinning projectile, a casing, a barrel rotatably mounted in the casing, the barrel adapted to engage the projectile to spin it, a spindle mounted in the casing, a spring interposed between the barrel and spindle, and detent mechanism including a toothed wheel in the casing for maintaining the spring in tension, the barrel having a flange and there being a disc between which and the wheel the flange is embraced and secured, means to secure the disc and wheel together, one end of the spring being secured to said means.

4. A propelling device for a spinning projectile comprising, a main substantially cylindrical casing including a side wall forming member having substantially parallel edges separated peripherally of the cylinder to provide a slot extending parallel to the axis of the cylinder, the slot being open at 125 130

one end of said member, a rotatable barrel carried by the casing and adapted to engage a projectile to spin the same, a spindle extending into the barrel, means to secure the 5 spindle in fixed relation to the casing, a torsion spring operatively connecting the spindle and barrel for rotating the barrel, detent mechanism within the casing, including a toothed wheel on the barrel and a trigger 10 member pivoted on the spindle and adapted to extend through the slot, the trigger while on the spindle being associatable with the aforesaid parts by inserting the trigger through the open end of said slot, and an 15 end closure member for the casing, said closure member fitting the cylinder side wall forming member and closing said open end of the slot.

In testimony whereof, I hereunto affix my 20 signature.

AUGUST KRASTIN.
